ARNOLD A. STEPHENS, OF DAVENPORT, IOWA

AUTOMOTIVE PISTON

Application filed December 30, 1926, Serial No. 158,110. Renewed September 27, 1930.

This invention relates to pistons for internal combustion engines particularly of the automotive type, and more especially to that type of piston composed of a non-ferruginous body.

It has been suggested heretofore to lessen piston friction in internal combustion motors by substituting for a cast iron piston one composed of a lighter material, such as an aluminum alloy. Such attempts have not been entirely successful. The substituted pistons have proved generally inefficient in operation. This has been due primarily to clearance problems. The aluminum material used while of less specific gravity than iron has greater thermal expansion and hence in order to prevent scoring of the cylinder walls, when the piston was operating at normal running temperatures, a relatively large initial clearance had to be allowed.

Attempts have been made to eliminate these disadvantages inhering in aluminum pistons. The proposed constructions comprehended two general types. The first type comprised a piston body of aluminum, the skirt of which was split at one or more places. The other type included pistons having aluminum bodies which were provided with some means to prevent the expansion of the skirt. These pistons while presenting some advantages were not entirely satisfactory. The split skirt type did not insure the requisite strength. The reinforced skirt type was subjected to great strains due to the restraining of the normal expansion.

It is an object of this invention to provide a piston of a material having a specific gravity less than iron which operates in a cylinder with a minimum of clearance.

Another object is to provide a composite piston comprising aluminum and ferruginous portions.

A further object is to provide a piston having an aluminum body and easily replaceable sections of a material of less thermal expansion than aluminum.

With these and other equally important objects which will appear more fully from the following description, my invention comprehends a piston having an aluminum body

portion which is provided with exterior expandable circumferential sections of a material having a coefficient of thermal expansion closely approximating that of the cylinder bore, and the provision of means cooperating with the sections and body to determine the expansibility of the sections.

To facilitate an understanding of the invention there is shown in the accompanying drawings a device which mechanically embodies the principles of my invention. In these drawings the identifying numerals refer to similar parts throughout the several views, of which

Figure 1 is an elevation of a piston; 65

Fig. 2 is a section on the line 2—2 of Fig. 1;

Fig. 3 is a sectional view similar to Fig. 2 showing a modification of the device;

Fig. 4 is an enlarged detail view of the restraining member mounted in position; 70

Fig. 5 is a view similar to Fig. 2 showing a further modification;

Fig. 6 is a perspective view of the restraining member.

In the drawings is shown a full skirted piston of an aluminum alloy having a head portion 1 and an integral continuous skirt portion 2. The skirt portion is formed with integral wrist pin bosses 3. It will be understood that these bosses are provided with bushings which support the journals of a wrist pin in the conventional manner. The bosses may be, and preferably are, formed with a plurality of reinforcing flanges. It is also desirable to tap the bosses to provide a passage for lubricating hydrocarbons to the wrist pin bearings. 75

The head portion of the piston is cast with grooves to receive the compression rings 4 and 5 and an oil ring 6. The head portion is also formed with a relatively wide and deep groove to receive a separate annular bearing section 7. This section is composed of a metal having a coefficient of thermal expansion very nearly equal to that of the material of the cylinder bore. This may be of a ferruginous material, such as cast iron. It is to be understood that the term "ferruginous" is used in the specification to designate material which has the thermal properties of iron, while by 100

the term "aluminous" is comprehended the various alloys of a specific gravity which is relatively small as compared with iron. The piston skirt at a point below the wrist pin bosses is provided with a second annular section 7. These sections are of the same structure so that a description of but one will be given, it being understood that what is said of the one applies equally to the other.

5 The piston skirt may be provided with an integral quadrantal extending portion on its thrust side. This protruding segment extends the full length of the piston skirt and serves as a bearing surface as described in my co-pending application Serial No. 101,940. As is 10 shown in Fig. 2, the annular section 7 is nested within the confines of groove 8, which, as has been intimated, is relatively wide and deep as compared to the compression ring grooves. 15 The groove 8, as shown, extends completely around the exterior surface of the piston body and is of the same width and depth throughout its circumference.

20 Positioned between the ring 7 and the bottom of the groove is a resilient member 9. This member preferably is a polygonal ribbon spring extending approximately three-quarters of the circumference of the piston skirt and presents a resilient backing for the 25 annular section 7 on all but the thrust side of the piston. Interposed between the section or ring 7 and the groove bottom at the thrust side of the piston is an arcuate filler member 10. This member is of substantially 30 the same segmental length as the extending thrust segment hereinbefore described.

35 As shown particularly in Fig. 4, the backing member 10 is bored to present a round aperture 11. The backing member is adapted to receive the restraining member 12. This 40 comprises a round base plate 13 having integral parallel projections 14. The top faces 15 of the projections are angularly disposed with respect to the horizontal plane of the base plate 13 and the side faces 16 converge 45 towards each other, for a purpose to appear more fully hereinafter. The ends of the projections 14 extend beyond the circumference of the base plate. It will be appreciated that 50 the backing member 10 can be prepared for the reception of the restraining means by boring a hole therethrough of the same diameter as that of the base plate 13.

55 The annular section 7 is channeled at 17 to receive the extensions 14. As will be observed from an inspection of Fig. 3, the channels 17 are considerably wider than the members 14 so that the annular sections may move circumferentially with respect to the piston body.

60 The assemblage and operation of the device will be apparent from the foregoing description. When the piston is to be assembled the resilient members 9 are placed in the two grooves 8 so that the gap between their

ends coincides with the extended thrust segment. The filler block, which has been previously bored and fitted with the restraining member is then placed in the groove. As was alluded to hereinbefore, the extensions 14 project beyond the circumference of the base plate 13. When the assembled backing plate and restraining means are positioned in the groove the ends of the extensions lie closely adjacent the groove lands and thus prevent any twisting movement of the restraining member in the socket of the filler block. The annular split sections 7 are then forced over the sides of the piston until they register with the grooves, the projections 14 taking into 70 the channels 17.

75 Under the action of the resilient member 9 the section 7 will expand. The bottom of the channel 17 will ride upon the inclined faces 15 and provide a snug engagement therebetween. The inclination of the faces 15 in conjunction with the angularity of the side faces provide, in effect, an undercut which insures a more positive engagement of the restraining means with the ring section. It 80 will be seen that the ring will be expanded, under the action of the spring 9, to the limit allowed by the restraining means. The described arrangement of elements allows free contraction but only a determinative expansion of the ring.

85 When the piston is installed the sections 7 fit flush with the cylinder bore. After the preliminary running in, the rings will be worn down to a glazed surface and a desirable 90 small clearance between the bearing sections and cylinder bore will obtain. By preventing undue expansion of the ring, seizing or scoring is precluded. The interposition of the resilient medium between the ring and 95 piston body allows the latter to freely expand or contract under varying cylinder temperatures without affecting the circumference of the ring sections, and thus provide a piston which combines the advantages attending the use of a piston of a light weight and one of 100 small clearance.

105 In Fig. 3 is shown a modification of the piston depicted in Fig. 1. In this device the backing plate is eliminated. The groove 8 is 110 cast so that it presents varying depths, the portion 8' being of less depth than the remainder of the groove so that the rings 7 rest 115 flatly against this portion. This provides a simpler structure susceptible of easy assembly. In this case the piston body, in the center of the shallow part of the groove, is spot bored. The restraining member 12 is 120 then inserted directly in the piston body.

125 A further modification of the device is shown in Fig. 5. By proper choice of materials the extending member 12 may serve not only to limit the expansion of the ring section, but it may also directly take the thrust of the ring. As shown, in this figure, the re- 130

silient member 9 is extended around nearly the entire circumference of the piston, the free ends being positioned adjacent the restraining means 12. By providing a wide 5 base plate for the ring engaging extensions 14, a structure rugged enough to take the piston thrust is insured. The relatively large piston contacting area presented by the base plate allows a greater distribution of this 10 thrust. The inclination of the ring engaging faces 15 insures a flat engagement with the interior of the ring and thus minimizes the danger of breakage.

It will now be seen that I have provided a 15 piston construction which is very light and of great strength, operable in a cylinder bore with a small clearance. The advantageous results of the device are accomplished by the use of relatively few, simple parts which are 20 inexpensive to manufacture and easy to install and replace.

I claim:

1. A restraining means for a bearing ring of the character described comprising a substantially circular base plate and chord extensions formed integral with the plate to slidably engage the internal face of the bearing ring and thereby limit its circumferential expansion.

2. A piston comprising a head and skirt formed with wrist pin bearings, compression rings carried in grooves in the piston head, a plurality of annular expandible sections of a greater width than the compression rings mounted above and below the wrist pin bosses, means to restrain the expansion of the sections and transmit the thrust of the piston directly to the section comprising a circular plate seated in the piston body and integral extending parallel chord like portions adapted for sliding engagement with the sections.

3. A piston comprising a body portion including a head and skirt, the body portion being bored at one side, a separate expandible section carried by the piston, a restraining means including a portion seated in the bored portion of the piston and a plurality of extensions for engaging the internal face 50 of the sections to restrain their expansion.

4. A piston having a head and skirt, a plurality of annular expandible sections mounted in grooves above and below the wrist pin bosses, a filler member interposed 55 between the ring and grooves, means to restrain the expansion of the sections comprising a circular plate fitting in the filler member and having integral projecting portions adapted to engage the sections.

5. A piston comprising a head and continuous skirt of an aluminous material, separate annular expandible extensions of a material of different thermal expansion than aluminium, and means detachably engaging 65 the piston body and sections comprising a

circular base plate adapted for engagement with the piston body, and a plurality of extensions on the plate adapted to engage said separate annular expandible sections for restraining their expansion.

70

In testimony whereof I affix my signature.
ARNOLD A. STEPHENS.
